(57) **CLAIM**

The ornamental design for a dispenser, as shown and described.

DESCRIPTION

FIG. 1 is a top, front, right side perspective view of a dispenser;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom view thereof.

The dot-dash broken lines represent boundaries of the claimed design and form no part of the claimed design. All other broken lines represent portions of the dispenser that form no part of the claimed design.

1 Claim, 6 Drawing Sheets
